UNITED STATES PATENT OFFICE.

GEORGE HARGREAVES, OF DETROIT, MICHIGAN.

VENTILATING SEWERS.

SPECIFICATION forming part of Letters Patent No. 321,719, dated July 7, 1885.

Application filed October 20, 1884. (No model.)

To all whom it may concern:

Be it known that I, GEORGE HARGREAVES, a citizen of the United States, residing at Detroit, in the county of Wayne and State of Michigan, have invented certain new and useful Improvements in Ventilating Sewers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a vertical longitudinal sectional view of my device. Fig. 2 is a detail view of the device for operating the doors on the openings into the sewer. Fig. 3 is a modification of the air-opening into the sewer. Fig. 4 is a sectional detail view.

This invention relates to improvements in ventilating sewers and consuming the sewer-gas by fire, and is intended to draw the ventilating-air into the sewers from the lowest and most impure stratum of the atmosphere nearest the ground or earth, and thereby destroy any germs of disease that may exist there.

The invention consists in the construction, novel arrangement, and adaptation of devices, as will be hereinafter more fully set forth and claimed.

In the accompanying drawings, A represents the vertical longitudinal section of a sewer, of which a represents the sewage, and a' the air-space above the same.

A' is the mouth of a similar sewer at right angles to and opening into A.

a² is the tube or flue by which the sewer A, and, if desired, A', open into the chimney B, of which b is the grate and fire, b' the ash-pit, and b² the foundation.

b³ is a chute by which fuel is introduced to the fire, and b⁴ is an opening opposite the chute, through which the fire is raked and the coal distributed. In some cases it is preferable to arrange the chimneys at the lower ends of the sewers instead of the upper ends, as shown in the drawings.

C are the tubes or flues that admit the air to the sewers. The flues may be either straight or inclined, and may have the same diameter

throughout, or may be smaller at their lower ends than at their upper, as shown.

c c are the gratings covering the flues C C, and c' c' are the doors or valves at their lower ends. Each of these valves opens inwardly on its hinge, and is opened and closed by means of the wire or metal chain c², connected to it opposite its hinge, and passing through a proper director near the end of the flue C, thence over the pulley c³, whence it rises through a proper opening, and is attached to the drum c⁴, and actuated by the lever c⁵ on the said drum. Each door has its own proper chain or wire, lever, and drum, and all the drums turn on the same rod or shaft, c⁶, fixed at any proper point to actuate the valves. The valves may be kept at any point of opening by means of a ratchet and pawl, or other proper means, connected to the drums of each. When the flues C C have their lower ends smaller than their upper, the valves are dispensed with, as shown.

D D are floats, made of any proper material, which show what quantity or height of water is in the different parts of the sewer. The floats D D have attached to them the cords or metal chains d d, which first pass over the pulleys d' d', thence run to the pulleys d² d², below which they turn and ascend through proper openings, turn over the pulleys or rollers d³, each of which has a bearing on the upright or standard d⁴, and have attached to their depending ends the weights d⁵ d⁵. The standard d⁴ is placed near the levers and drums, so that the person operating the latter may know the height of water in the sewer. As the water ascends in the sewer the float D also ascends and the weights d⁵ descend upon the standard. The valves c' are usually set less widely open as the sewer rises, because it is desirable to draw more air from the lower and more impure strata of the atmosphere outside. There is also caused thereby a greater range of draft in the sewer when the chimney is at the upper end. When the flues C are of smaller diameter at their lower ends than at their upper ends, their openings into the sewer grow less as they approach the chimney, except in some cases, where the latter is at the lower end of the sewer.

Having thus described my invention, what

I claim as new, and desire to secure by Letters Patent, is—

1. The combination, with the sewer, of a chimney having a fire-place therein, a flue connecting the sewer with the chimney below the fire-place, vertical flues leading from the outer surface to the sewer, with valves at their lower ends, a shaft having drums provided with levers, and cords connecting the vertical flue-valves with the said drums, substantially as specified.
2. The combination, with a sewer, of a vertical frame or standards having horizontal rollers, floats arranged in the sewers, and

cords or chains connecting the floats and weights, substantially as specified.

3. The combination, with a sewer and flues having hinged doors or valves at their lower ends, of a horizontal shaft having one or more drums, and a lever-handle, and cords connecting the valves and drums, substantially as specified.

In testimony whereof I affix my signature in presence of two witnesses.

GEORGE HARGREAVES.
